UNITED STATES PATENT OFFICE

162,534

MATERNITY SKIRT

Arlene J. Greendale, Chicago, Ill.

Application August 23, 1948, Serial No. 148,255

Term of patent 14 years

(Cl. D3—26)

To all whom it may concern:

Be it known that I, Arlene J. Greendale, a citizen of the United States of America and resident of the city of Chicago, county of Cook, and State of Illinois, have invented a new, original, and ornamental Design for a Maternity Skirt, of which the following is a specification, reference being had to the accompanying drawing, forming a part thereof.

Fig. 1 is a front elevational view of a maternity skirt, showing my new design.

Fig. 2 is a rear elevational view thereof.

Fig. 3 is an enlarged fragmentary front elevational view thereof.

I claim:

The ornamental design for a maternity skirt, substantially as shown.

ARLENE J. GREENDALE.
